(57) **CLAIM**

The ornamental design for a luggage, substantially as shown and described.

DESCRIPTION

FIG. 1 shows a perspective view of a design of a luggage with its handle in a retracted configuration.

FIG. 2 shows a front view of the design.

FIG. 3 shows a rear view of the design.

FIG. 4 shows a right side view of the design.

FIG. 5 shows a left side view of the design.

FIG. 6 shows a top view of the design.

FIG. 7 shows a bottom view of the design.

FIG. 8 shows a right side view and a partial interior view of the design in a partially open configuration and with the handle in a protracted configuration.

FIG. 9 shows a front interior view of the design in an open configuration showing a laundry bag of the design in a deployed configuration; and,

FIG. 10 shows a front interior view of the design in an open configuration showing a compression pad exposed and the laundry bag of the design in a stored configuration.

The broken lines shown in the drawings represent unclaimed portions of the luggage and form no part of the claimed design.

1 Claim, 10 Drawing Sheets
